UNITED STATES PATENT OFFICE

2,414,961

ELECTROMAGNETIC DEVICE

Charles R. Mason, Ballston Spa, and Lawrence A. Burton, Schenectady, N. Y., assignors to General Electric Company, a corporation of New York

Application October 26, 1944, Serial No. 560,374

9 Claims. (Cl. 200—111)

1

Our invention relates to improvements in electromagnetic devices and more particularly to improvements in electromagnetically actuated circuit controlling devices such as contactors, relays and the like.

In electromagnetically actuated circuit controlling devices such as contactors, relays and the like, wherein a movable rigid bridging contact is actuated under bias to engage rigid stationary contacts upon movement of an armature to the attracted position, the bridging contact tends to rebound when it strikes the stationary contacts. This tendency is accentuated if the armature is rigidly associated with the movable contact since the relatively heavy mass of the armature is added to that of the movable contact and the sudden stopping of both produces a greater reaction and, consequently, a greater tendency to rebound. The consequent bouncing of the parts causes arcing which not only produces needless wear of the contact surfaces, but also renders the circuit controlling action of the device uncertain. Such uncertainty of action cannot be tolerated in devices for use on warcraft and especially aircraft. Moreover, the bouncing action tends to produce general wear and misalignment, both of which result in unsatisfactory operation. It is usual in electromagnetically actuated circuit controlling devices such as contactors and the like to have the armature solidly engage its cooperating pole piece in the closed circuit position of the contacts. With such arrangements, it is necessary to make special provision not only to prevent rebound, but also to compensate for contact wear or to accept a continuing decrease in contact pressure with a resulting decrease in conductivity in consequence not only of contact wear but also battering of the attracting surfaces of the armature and its cooperating pole piece. Such arrangements do not insure the maximum of contact pressure for a given attractive force or any increase in pressure as contact wear occurs. As far as we are aware, the arrangements heretofore proposed are complicated, costly and in general unsatisfactory when the devices are subject to shock and when space and weight are critical factors as in aircraft.

An object of our invention is to provide for electromagnetically actuated devices an improved contact and armature mounting which is relatively simple, economical, light in weight and compact. Another object of our invention is to provide an improved contact and armature mounting which substantially eliminates rebound. A further object of our invention is to

2

provide, in an electromagnetically actuated circuit controlling device, an improved arrangement for maintaining a relatively high contact pressure with compensation for contact wear such as to insure even higher contact pressure as wear occurs. These and other objects of our invention will appear in more detail hereinafter.

In accordance with our invention, we provide a relatively simple and compact armature and movable contact mounting comprising two springs, one to bias the armature to the unattracted or circuit open position and the other to permit relative movement between the contacts and the armature after the contact has reached the closed circuit position during the movement of the armature to the attracted position. Also in accordance with our invention, we so arrange the parts of the electromagnetic device that in the circuit closed position of the armature there still remains a material air gap between the armature and its cooperating pole piece.

Our invention will be better understood from the following description when considered in connection with the accompanying sheet of drawings, and its scope will be pointed out in the appended claims.

In the accompanying drawing, Fig. 1 is a plan view of an electromagnetically actuated switching device embodying our invention, with parts broken away; Fig. 2 is a vertical sectional elevation on the line 2—2 of Fig. 1, showing the device in the circuit open position; Fig. 3 is a part vertical sectional elevation on the line 3—3 of Fig. 1, showing the device in the circuit open position; Fig. 4 is similar to Fig. 3, showing the device in the circuit closed position; and Fig. 5 is an exploded perspective view illustrating parts of the contact mounting shown in the illustrated embodiment of our invention.

In the accompanying drawing, we have illustrated an electromagnetically actuated device in the form of a contactor embodying our invention. As shown, this device comprises a shell 1 of suitable magnetic material within which is mounted an energizing winding 2 on a spool 3 of suitable nonmagnetic material. Within the shell 1, there is an adjustably positioned pole piece 4 which, as shown, is threaded into the shell and held in position by a lock nut 5. Above the shell 1, there is a cap 6 of suitable magnetic material. This cap has a hollow cylindrical portion 7 within which is mounted a bushing 8 of suitable nonmagnetic material for guiding an armature 9 during movement toward and from the tip of the pole piece 4.

For controlling a circuit by the movement of the armature 9, we provide two spaced stationary contacts such as silver blocks 10 which are suitably conductively secured to terminals 11. These terminals are secured to a base 12 of suitable insulating material by suitable means such as screws 13. This base is fastened to the cap 5 of the magnetic structure by suitable means such as screws 14. For bridging the gap between the stationary contacts 10, there is provided a bridging contact 15 which is carried by the armature 9 transversely thereof. The bridging contact is provided with silver block inserts 16 which engage the contacts 10 when the armature 9 is moved to the attracted position.

In order to return the bridging contact 15 to the unattracted or circuit open position, we provide a leaf biasing spring 17 carried by the armature transversely thereof and preferably at right angles to the bridging contact as shown. To provide abutments for the biasing spring 17 and also to prevent turning thereof, the ends of this spring are set in suitable notches 18 in the base 12. We have found that by tapering the biasing spring 17 as shown in Fig. 1 the bending stresses are more uniformly distributed throughout the spring than in a spring of uniform cross section. In consequence of this tapering, the effective life of the spring is increased without increasing the weight or space required by a sufficiently strong spring of different shape and having the same length of life as the tapered spring. In order to prevent turning of the biasing spring 17 relatively to the bridging contact 15, we provide guide means such as a saddle 19 having a pair of upward projections or flanges 20 between which the bridging contact is positioned and a pair of downward projections or flanges 21 which are at right angles to the flanges 20 and between which the biasing spring is positioned.

In order to prevent rebound of the movable parts as the armature 9 moves to the attracted position, we provide, in accordance with our invention, an arrangement whereby the armature is free to move relatively to the bridging contact 15 following engagement thereof with the stationary contacts 10. As shown, this arrangement comprises a cushioning leaf spring 22 which is supported on suitable abutting surfaces 23 formed, for example, by shaping the bridging contact 15 so that it is concave upward. For simplicity, the cushioning leaf spring 22 is preferably circular, as shown, since this eliminates the necessity for guides to maintain the spring in any particular alignment relatively to the bridging contact.

In order to maintain the assembly of the cushioning leaf spring 22, the bridging contact 15, the saddle 19, the biasing leaf spring 17 and the armature 9, we provide fastening or securing means such as a screw 24 which is threaded into the armature 9. This screw has a shouldered portion 25 which seats on a lock washer 26 tightly against the guide 19 to hold the biasing spring 17 against the top of the armature 9. To permit some tilting of the contact 15 relatively to the direction of movement of the armature 9 to and from the attracted position, the shouldered portion 25 of the screw 24 projects through a clearance hole in the cushioning spring 22 and also through a clearance hole in the bridging contact 15. This provides some freedom of movement of the contact 15 relatively to the stationary contacts 10 for better contact engagement. Above the shouldered portion 25, the screw 24 has an enlarged head portion 27 to re-

tain the cushioning spring 22 in position under a predetermined initial strain as shown in Fig. 3.

In order to maintain this armature assembly in position under a predetermined initial bias or strain, as shown in Fig. 3, we provide means such as a cross bar 28 abutting the head 27 of the screw 24. As shown, this bar is held in position under the heads of two diagonally opposite base screws 14. It will be apparent from Fig. 3 that, when the assembly screw 24 is seated tightly against the saddle 19, the cushioning spring 22 is placed under a predetermined strain or bias to hold the bridging contact 15 in place between the flanges 20 of the saddle 19.

In assembling the parts carried by the armature 9 at the upper end thereof, they are mounted in the order shown in Fig. 5, except for the lock washer 26, with the biasing contact 17 immediately adjacent the armature. Just above the biasing spring 17 is the saddle 19 with its flanges 21 embracing the parallel side edges 29 of the biasing spring 17. Resting on the guide 19 between the flanges 20 thereof is the central portion of the bridging contact 15. Above this contact and resting on the abutment faces 23 thereof is the circular cushioning spring 22. The foregoing parts are secured to the armature by the screw 24, which is threaded into the armature and screwed up tight against the lock washer 26 on the saddle 19. The shouldered portion 25 passes through clearance openings 30 and 31 in the cushioning spring 22 and the contact 15, respectively. When the assembly of the armature 9, the contact 15 and the leaf springs 17 and 22 is completed, the cushioning spring 22 is stressed to take the configuration shown in Fig. 3. When the armature is mounted in the electromagnet and the bar 28 is set in the restraining position, the biasing spring 17 takes the configuration shown in Fig. 2.

Upon energization of the winding 2 sufficiently to attract the armature 9 against the bias of the biasing spring 17, the armature starts toward the attracted position shown in Fig. 4. Until the bridging contact 15 engages the stationary contacts 10, the whole armature, contact and spring assembly moves as a unit against the bias of the leaf spring 17. When the bridging contact 15 engages the stationary contacts 10, however, movement of the armature 9 and the bridging contact 15 as a unit ceases, but the armature 9 is free to travel a desired distance since the cushioning spring 22 yields to permit movement of the armature 9 relatively to the bridging contact 15. When the cushioning spring reaches the limit of its movement to bear against the central portion of the bridging contact as shown in Fig. 4, the travel of the armature is completed, but there remains a desired air gap between the attracting surfaces of the armature and its pole piece 4. With this air gap, the full attractive effort of the magnet is available to maintain relatively high contact pressure and there is no battering of the attracting surfaces. Also, the air gap insures compensation for such wear of the contact surfaces as may reasonably be expected. Furthermore, as contact wear occurs, the contact pressure is increased by virtue of the decrease in the air gap. During the movement of the armature 9 between the time when the bridging contact 15 engages the stationary contacts 10 and the position of the armature shown in Fig. 4, there is no rebound of the bridging contact 15 since the armature has been free to travel toward the

final attracted position with the cushioning spring 22 absorbing the rebound forces.

While we have shown and described our invention in considerable detail, we do not desire to be limited to the exact arrangement shown, but seek to cover in the appended claims all those modifications that fall within the true spirit and scope of our invention.

What we claim as new and desire to secure by Letters Patent of the United States is:

1. In an electromagnetically actuated device, an armature, a biasing leaf spring tightly secured to said armature transversely thereof to prevent turning relatively thereto, means for guiding the ends of said biasing leaf spring to prevent turning of the armature, a contact carried by said armature and extending transversely thereof, said contact having spaced abutments on the side away from the armature, a cushioning leaf spring carried by said armature in a position to bridge the abutments on said contact, and means for securing the cushioning leaf spring and the contact to the armature including means for preventing rotation of the contact about an axis substantially parallel to the direction of movement of the armature to and from the attracted position arranged to allow some tilting of the contact relatively to said axis.

2. In an electromagnetically actuated device, an armature, a biasing leaf spring carried by said armature and extending transversely thereof, a movable contact carried by said armature and extending transversely thereof, said contact having spaced abutments on the side away from the armature, a cooperating stationary contact, a circular cushioning leaf spring carried by said armature in a position to bridge the abutments on said contact deflectable against said movable contact to limit the movement of the armature in the attracted direction after the movable contact engages the stationary contact whereby to limit the total movement of the armature to an amount materially less than the air gap between the armature and its attracting pole when the armature is in the unattracted position, and means for securing the springs and the contact to the armature arranged to allow some tilting of the movable contact relatively to the armature.

3. In an electromagnetically actuated device, a plunger armature, a biasing leaf spring carried by said armature and extending transversely thereof, a contact carried by said armature and extending transversely thereof, said contact having spaced abutments on the side away from the end of the armature, guide means for maintaining a predetermined angularity between said contact and said biasing spring, a circular cushioning leaf spring carried by said armature in a position to bridge the abutments on said contact, and means for securing the springs, the contact and the guide means to the armature with the contact tiltable relatively to the armature.

4. In an electromagnetically actuated circuit controlling device, an armature, a biasing leaf spring carried by said armature and extending transversely thereof, two spaced supports for said biasing spring mounted on opposite sides of the armature, a bridging contact carried by said armature and extending transversely thereof and having a concave outline on the side away from the armature, guide means for maintaining a predetermined angularity between said contact and said biasing spring, a cushioning leaf spring carried by said armature in a position to bridge the concavity of said contact, means for securing

the springs, the contact and the guide means to the armature with the contact tiltable relatively to the armature, and means for placing the biasing spring under a predetermined initial strain.

5. In an electromagnetically actuated circuit controlling device, a plunger armature, a biasing leaf spring mounted on one end of said armature and extending transversely thereof, two spaced supports for said biasing spring mounted on opposite sides of the armature, a bridging contact carried by said armature at one end thereof and having a concave outline on the side away from the armature, guide means for maintaining said wiping spring and said contact substantially perpendicular to each other, a circular cushioning leaf spring carried by the end of said armature in a position to bridge the concavity of said contact, means for securing the springs, the contact and the guide means to the armature with the contact tiltable relatively to the armature, and means abutting said securing means for placing the biasing spring under a predetermined initial strain.

6. In an electromagnetically actuated circuit controlling device, a rectilinearly movable armature, means for moving the armature to the unattracted position comprising a biasing leaf spring carried by said armature and extending transversely thereof and spaced supports for said spring on opposite sides of the armature, two spaced stationary contacts on opposite sides of said armature, a cooperating bridging contact carried by said armature and extending transversely thereof, spaced raised portions on the side of said bridging contact away from the armature, a cushioning leaf spring bridging the spaced portions of said bridging contact, fastening means engageable with said armature for securing the springs and the bridging contact to the armature with the bridging contact tiltable relatively to the armature, and stationary means engageable with said fastening means to place said biasing spring under a predetermined initial strain when the armature is in the unattracted position.

7. In an electromagnetically actuated circuit controlling device, a plunger armature, means for moving the armature to the unattracted position comprising a biasing leaf spring carried by the armature and extending transversely thereof and spaced supports for said spring on opposite sides of the armature arranged to prevent turning of the spring, two spaced stationary contacts on opposite sides of said armature substantially 90° from said supports, a cooperating bridging contact carried by said armature and extending transversely thereof, a saddle carried by said armature for maintaining the biasing spring and the bridging contact substantially perpendicular to each other, spaced raised portions on the side of said bridging contact away from the armature, a circular cushioning leaf spring bridging the raised portions on said bridging contact, a screw for securing the springs, the saddle and the bridging contact to the armature with the bridging contact movable relatively to the armature, a stationary member so positioned in contact with said screw and relatively to the supports of said biasing spring as to place the biasing spring under a predetermined strain when the armature is in the unattracted position.

8. In an electromagnetically actuated device, an armature, a pole piece, an energizing winding for effecting movement of said armature from the unattracted position toward said pole piece, means for biasing the armature away from the

pole piece, a stationary contact, a cooperating movable contact carried by the armature, a resilient coupling between the armature and the movable contact deflectable to permit a predetermined movement of the armature relatively to the movable contact after the movable contact engages the stationary contact on movement of the armature toward the attracted position, and means for preventing further deflection of said resilient coupling whereby to prevent further movement of the armature in the attracted direction, the construction and arrangement of parts being such that the total movement of the armature from the unattracted position to the final position is materially less than the gap between the pole piece and the armature in the unattracted position.

9. In an electromagnetically actuated device, a plunger armature, a stationary pole piece, an energizing winding for effecting movement of the armature from the unattracted position toward said pole piece, a leaf spring carried by said armature transversely thereof for biasing the arma-

ture away from said pole piece, two spaced stationary contacts, a cooperating rigid bridging contact carried by said armature transversely thereof at a predetermined angle to said biasing spring, a cushioning leaf spring freely supported by said contact at the edges thereof and connected to said armature at an intermediate point deflectable to permit a predetermined movement of the armature relatively to the bridging contact 10 after the bridging contact engages the stationary contacts on movement of the armature to the attracted position, said cushioning leaf spring being arranged to engage said contact at the end of said predetermined movement of the armature whereby to prevent further movement of the armature in the attracted direction, the construction and arrangement of parts being such that the total movement of the armature from the unattracted position to the final position is materially less than the gap between the pole piece and the armature in the unattracted position thereof.
